UNITED STATES PATENT OFFICE.

JOSEPH KELLER, OF LAURY'S STATION, PENNSYLVANIA.

DESIGN FOR TONGUE-SUPPORT.

Specification forming part of Design No. 5,204, dated August 15, 1871.

To all whom it may concern:

Be it known that I, JOSEPH KELLER, of Laury's Station, in the county of Lehigh and State of Pennsylvania, have invented a new and useful Design for Supports for Tongues of Harvesters, &c., of which the following is a specification:

My invention relates to devices for transferring the weight of the tongue of harvesters, &c., from the horses necks; and consists of a caster-wheel arranged to revolve in a suitable bearing rigidly attached to the side of the beam to which the tongue is secured.

In the accompanying drawing, Figure 1 is a side elevation of my device, and Fig. 2 is a plan view of the top of the same.

A is a beam tenoned at one end, *a*, to fit in the axle, frame, or other part of the machine. Its other end, *b*, is slotted or forked, in which slot the tongue B is hung so as to move freely therein. To one side of the beam A a bearing, C, is rigidly attached by means of bolts, &c., a piece, *c*, extending underneath the beam and likewise secured thereto, serving to strengthen the same. This may all be made in one piece—cast or otherwise. A clevis, D, is provided with a journal or pivoted projection, *d*, which is secured in the bearing C by means of a pin passing through its end, or the said end may be threaded and a nut

screwed thereon. The clevis and part *d* are made in one piece. A suitable wheel, E, is hung, by means of journals, in bearings in the ends of the clevis.

It will be seen that, by placing the wheel at or near the end of the stationary beam, all the weight of the front part of the machine is transferred to the wheel, and thus the strain on the horses is greatly lessened and an easier motion is given to the machine.

What I claim is—

1. The design for a support for tongues of harvesters, &c., as herein set forth and shown.
2. The shape or conformation of the clevis D, as and for the purpose set forth.
3. The shape or conformation of the bearing C with the piece or support *c*, as and for the purpose set forth.
4. The shape or conformation of the clevis D, formed with the journal *d*, as and for the purpose set forth.
5. The shape or conformation of the bearing C, as and for the purpose set forth.

To the above I have signed my name this 6th day of August, 1870.

JOSEPH KELLER.
